UNITED STATES PATENT OFFICE.

WILLIAM L. DODGE, OF MAPLEWOOD, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,393,352.

Specification of Letters Patent. Patented Oct. 11, 1921.

Application filed September 22, 1919. Serial No. 325,518.

To all whom it may concern:

Be it known that I, WILLIAM L. DODGE, a citizen of the United States, residing at Maplewood, in the county of Essex, State 5 of New Jersey, have invented certain new and useful Improvements in Telephone Systems, of which the following is a full, clear, concise, and exact description.

This invention relates to telephone systems and more particularly to such systems in which the signals for a plurality of trunk lines extending between stations or central offices are controlled over a single signaling path common to such trunk lines and likewise extending between the two stations.

An object of this invention is the provision of improved signaling means for systems of this character.

In attaining this object of the invention 20 there is provided at each end of the common signaling path an intermittently operating commutator or distributor for individually associating the trunk lines with the common signaling path and for transmitting and receiving thereover code combinations or code signals individual to the various trunk lines, the code of which is determined by an intermittently operating selector switch controlled by the individual 25 trunk lines and controlling the polarity of signaling current connected with the sending segments of the sending distributor which control the selection of the trunk line at the receiving end, and a pole changing 30 switch individual to and controlled by each trunk line for determining the polarity of signaling current connected with another of the sending segments of the sending distributor for the purpose of determining the 35 signal of the selected trunk line to be operated.

A further object of this invention concerns means provided for testing the signaling portion of such telephone systems 40 and the associated apparatus controlling the transmission of code signals over the common signaling path.

In attaining this second object of the present invention, switching apparatus normally connecting the signaling path and the signal control apparatus thereof with signal control leads individual to and associated

with the various trunk lines and normally connecting a duplicate signaling path and associated signal control apparatus with 55 testing equipment comprising testing keys, signals and controlling relays, when actuated simultaneously disconnects the individual signal control leads from the first and connects these leads with the second common 60 signaling path and associated signal control apparatus, and disconnects the testing equipment from the second and connects it with the first signaling apparatus and associated signal control apparatus, whereby 65 the signals for the trunk lines may be transmitted over the second or duplicate signaling path, while the first signaling path and associated signal control apparatus are being tested.

A still further object of this invention is the provision of means for determining whether the signal sending and signal receiving distributors at the opposite ends of the common signaling path are operating in 70 synchronism.

For a more complete understanding of this invention reference should be had to the following description considered in connection with the accompanying drawings, 80 in which Figures 1 and 2 when placed end to end with Fig. 1 to the left of Fig. 2 illustrate one embodiment thereof. For convenience, where like apparatus is employed at offices X and Y, it will be designated by 85 the same reference characters, that at office X without, and that at office Y with primes.

Referring to the drawings, there is shown a cord circuit F located at an office X for 90 establishing connections with a trunk line L2 extending from the office X to the office Y. The trunk line L2 may be connected with a telephone line G terminating at the office Y. While but one trunk line L2 is shown 95 it is to be understood that this is for the purpose of convenience only and that this invention contemplates a plurality of such trunk lines.

To provide for the transmission of supervisory and other signals between operators and between operators and subscribers in connection with the establishment of connections over the various trunk lines, a signal

ing path P common to the plurality of telephone trunk lines extends from central office X to the central office Y.

- The various trunk lines to which the signaling path P is common are individually associated with the signaling path by means of intermittently operating distributors similar to the so-called start-stop distributors employed in printing telegraphy.
- 10 These distributors also serve to transmit and receive coded signals originating at the respective offices. At the office X there is employed a transmitting or sending start-stop distributor TD for transmitting code signals over the common signaling path P to the office Y at which is located a receiving start-stop distributor RD' for receiving the transmitted code signals. For the purpose of associating the individual trunk lines with the sending distributor TD, each trunk line is provided with signal control leads A, B and C individual thereto and a starting lead ST common to the trunk lines for controlling an automatic selector switch H at the office X having eight brushes, designated a, b and 1 to 6 inclusive. The brushes a and b and the associated contacts are for the purpose of rendering the switch individual to particular trunk lines, while the brushes 1 to 3 inclusive and their associated contacts control the polarity of signaling current connected with the individual sending segments of the transmitting distributor TD, thereby determining the codes of the signals to be transmitted by this distributor. The sixth brush connects with the sixth individual sending segment of sending distributor TD any one of the C signal control leads associated with the trunk lines, there being apparatus individual to the various trunk lines for determining the polarity of the signaling current connected with these circuit leads. The brushes 1 to 5 inclusive and associated contacts determine the trunk line to be selected at the receiving end of the common signaling path P while the brush 6 and associated contacts select the signal of the selected trunk line to be operated.
- 50 The selector switch H has its brushes a, b, and 1 to 6 mounted upon a common shaft driven step by step by a motor magnet MM initially controlled by a start magnet 28 connected in the start lead or conductor ST common to the trunk lines. Brushes 1 to 6 are connected directly with the respective individual sending segments of the sending distributor TD. Brush a of the selector switch H is connected with the energizing winding of a relay 35 which controls the stopping of the motor magnet MM and the energization of the release magnet TDM of the sending distributor TD. Brush b is connected with a contact of relay 35 for the purpose of assisting in the control of the switch as will more fully hereinafter appear. A slow release relay 39 and a release relay 37 associated with the automatic selector switch H are controlled by local controlling segments of the sending distributor TD for reasons which will more fully hereinafter appear. A plurality of contacts equal in number to the number of trunk lines to which the selector switch H is common are associated with each brush thereof. The contacts associated with the different brushes are mounted at different levels in position to be engaged by the respective brushes as they are rotated by the motor magnet MM. A total of eight contacts, one from each level is allotted to each trunk line, and these several contacts are simultaneously engaged by the respective brushes as will more fully hereinafter appear. Those contacts of the levels a and b and individual to trunk line L2 are connected with signal control leads A2 and B2 respectively individual to trunk line L2. To those contacts of levels 1 to 5 and individual to trunk line L2 are directly connected currents of polarities forming the first five impulses of the code signal representing trunk line L2, while the polarity of the sixth impulse of the code signal is determined by the polarity of current connected with the allotted contact of the sixth level and may be either positive or negative, depending upon the energized or deenergized condition of a pole changing relay 24 individual to trunk line L2. This pole changing relay 24 controls the polarity of current connected with signal control lead C2 connected with the contact of the sixth level allotted to trunk line L2.
- In order to translate the code signals received at the office Y by the receiving distributor RD', and to select the appropriate trunk line terminating thereat, a pyramid selecting relay combination of well-known type is provided and is controlled in a well-known manner by means of locking relays 105 whose energizing circuits are associated with the individual receiving segments of the receiving distributor RD'. For controlling the signals to be operated, each trunk line is provided with a signal receiving 110 lead E'.
- Referring more in detail to the apparatus provided at the office Y for receiving the code signals transmitted over the common signaling path P, the receiving distributor RD' is controlled by differential polarized relay 50' connected in the signaling path P. When the alternate contact of relay 50' is first closed, the release magnet RDM' of the receiving distributor RD' is energized and 120 releases the brush arm controlled thereby, which thereupon makes one complete revolution. Relay 58', which is normally energized over a circuit including segment 55', the brush arm and the inner ring 52' of the 125
- 65 130

receiving distributor RD', holds open its contact which is in the locking circuits of locking relays 61' to 66' inclusive, whose energizing windings are connected with the respective individual receiving segments 1' to 6' inclusive of the receiving distributor RD'. Relays 61' to 64' inclusive control relays 67' to 81' inclusive comprising the pyramid selecting relay combination which co-operates with locking relay 65' to select the signal receiving conductors E' terminating in contacts of relays 74' to 81' inclusive. Locking relay 66' controls the polarity of signaling current connected with the selected signal receiving conductor or lead for determining the signal to be operated.

For transmitting over the common signaling path P signals originating at the office Y, sending equipment comprising a sending distributor selector switch and associated control apparatus and signal control leads similar to that described in connection with the office X is provided at the office Y. This apparatus, for purpose of convenience, is represented by the dotted rectangle designated SE'. Likewise, in order that the code signals transmitted from the office Y to the office X over the common signaling path P may be properly received and translated, and the appropriate trunk lines selected, there is provided at this office X receiving equipment comprising receiving distributor RD, pyramid selecting relay combination, control locking relays and signal receiving leads, such as was described in connection with the office Y. This receiving equipment at the office X, for the purposes of convenience, is represented by the dotted rectangle RE.

As shown in the drawings, a duplicate common signaling path DP extends between the two offices. For transmitting and receiving over this duplicate common signaling path DP code signals resulting from signals originating at either of the offices there is associated with this duplicate common signaling path DP sending and receiving equipment located at each of the offices. The sending and receiving equipment for this duplicate signaling path located at the office X is indicated by the dotted rectangles DSE and DRE, and that located at the office Y is indicated by the dotted rectangles DSE' and DRE'. In order that the common signaling paths and the associated sending and receiving distributors may be tested, there is provided testing equipment which may be associated with either of the signaling paths. A portion of this testing equipment is individual to the trunk lines while another portion is common thereto. Since the testing equipment located at the two offices is identical, that located at the office X will be described, while that located at the office Y will not be

described but will merely be designated by the same reference characters with the addition of prime ('). The portion of the testing equipment which is individual to a trunk line and which is located at the office X comprises two signal initiating keys M and N and a signal receiving relay D and a signal lamp O controlled thereby, while the common testing equipment comprises a relay 119 and a signal 120 controlled thereby. At each office the testing equipment is normally associated with the duplicate signaling path DP through normally closed contacts of switches, while the individual trunk line is associated with the signal control apparatus of the signaling path P through normally closed contacts of similar switches. These switches at the office X for the trunk line L2 are shown within the dotted rectangle K2. Those in the upper row control the connection and disconnection of the trunk lines with the signaling paths, while those in the lower row control the connection of the testing equipment with the signaling paths. Similarly arranged switches for the trunk line L2 and serving the same purposes at the office Y are shown within the dotted rectangle K'2.

Having in mind this brief description of the invention shown in the drawings, it is thought that the invention will be thoroughly understood from a description of the operation of the system shown. First, the setting up and breaking down of a connection between the cord circuit F and the telephone line G will be described, and next the testing of the signaling system will be described.

Connection of cord circuit F with trunk line L2. 105

The operator at the office X, desiring to establish connection with the telephone line G terminating at the office Y, communicates with the operator at office Y over an order wire (not shown). The operator at the office X ascertaining from the operator at the office Y that the connection with the telephone line G is to be completed by way of the trunk line L2, inserts calling plug 20 of the cord circuit F into jack 21 of the trunk line L2. Relay 22 thereupon operates over a circuit from battery through supervisory lamp 23, sleeve contact of the plug 20 and the jack 21 and winding of relay 22 to ground. Lamp 23 is not lighted at this time due to the high resistance of the winding of relay 22. Relay 22 in operating causes the operation of pole changing or switching relay 24 over a circuit from battery through the normal contact of relay 25, winding of relay 24 and contact of relay 22 to ground. Relay 24 in operating completes a locking circuit for itself through a middle alternate contact and its winding 130

- and the contact of relay 22 to ground. Upon the operation of relay 24, relay 25 operates over a circuit from battery, through a middle alternate contact of relay 24, resistance 26 and winding of relay 25 to ground. Relay 25 thereupon locks up through its left-hand alternate contact, resistance 26 and its own winding to ground. The operation of relay 24 also connects positive signaling battery with the signal control lead C2 and connects the signal control lead B2 with one terminal of the winding of relay 27. The operation of relay 25 grounds the signal control lead A2 and the common start lead ST.
- Upon the grounding of the common start lead ST, start magnet 28 associated with the automatic selector switch H operates over a circuit from battery through the winding of magnet 28, the start lead ST, a normal contact of the switch K, right-hand contact of relay 30, right-hand alternate contact of relay 25 and a normal contact of relay 27 to ground. Start magnet 28 upon being energized completes a circuit for the motor magnet MM which thereupon interrupts its own circuit rotating the brushes of the selector switch step-by-step until the brush *a* engages the contact to which the signal control lead A2 is connected, whereupon relay 35 operates over a circuit from battery through the left-hand winding of relay 35, brush *a*, a normal contact of switch K, signal control lead A2, middle contact of relay 30, middle alternate contact of relay 25 and a normal contact of relay 27 to ground. With the brushes of the automatic selector switch H stopped in engagement with the contacts allotted to trunk line L2, the brushes 1 to 6 inclusive connect positive signaling current with the first, third, fourth and sixth sending segments of the sending distributor TD and negative signaling current with the second and fifth sending segments thereof. Relay 35 in operating immediately locks up over a circuit from battery through its right-hand winding and left-hand alternate contact and the contact of release relay 37 to ground. Relay 35 in operating also opens its normal contact, thereby stopping the operation of the motor magnet MM and closes its middle alternate contact, thereby causing the operation of relay 27 over a circuit from battery through a middle alternate contact of relay 24, left-hand contact of relay 30, winding of relay 27, right-hand alternate contact of relay 24, signal control lead B2, a normal contact of the switch K, brush *b* of the selector switch H, middle alternate contact of relay 35, normal contact of relay 39 and the normal contact of release relay 37 to ground. Relay 27 in operating locks up over a circuit from battery through a middle alternate contact of relay 24, left-hand contact of relay 30 and 65 the winding and alternate contact of relay 27 to ground. Relay 27 in operating opens its normal contacts, thereby removing the ground connection from start lead ST and signal control lead A2. The energizing circuits of start magnet 28 and relay 35 are thereby opened. Relay 28 thereupon releases its armature. The operation of relay 27 serves to disconnect automatic selector switch H from the trunk line L2, so that 70 the selector switch H is free to be associated with any other of the trunk lines to which it is common.
- Referring now to the operation of relay 35, the closure of the right-hand alternate 80 contact of this relay causes the energization of release magnet TDM of the transmitting distributor TD over a circuit from battery, through ring 40, brush arm, segment 45, right-hand alternate contact of relay 35 and 85 the winding of release magnet TDM to ground. This magnet in attracting its armature releases the brush arm of the sending distributor TD, which thereupon makes a complete revolution successively engaging 90 the various segments of the distributor. Upon engagement of the brush arm with the starting segment *s*, positive battery is connected with the common signaling path P, thereby causing the energization of the 95 differential polarized magnet 50' at the office Y. As the brush arm moves out of engagement with the segment 45, the release magnet TDM is deenergized, restoring its armature to normal position for engaging and 100 stopping the brush arm at the conclusion of its complete cycle. The engagement of the brush arm with the segment 42 causes the operation of a slow release relay 39 over a circuit from battery through the segment 40, 105 brush arm, segment 42 and the winding of slow release relay 39 to ground. This relay 39 thereupon removes ground from the brush *b* of the automatic selector switch H. As the brush arm successively engages the 110 individual sending segments 1 to 6, signaling current of the polarities connected with these segments are successively connected with the common signaling path P which terminates on the common sending ring 43. 115 These polarities are such that the sending distributor TD transmits a coded signal comprising six impulses, the first, third, fourth and sixth of which are positive and the second and fifth are negative. When 120 the brush arm moves out of engagement with the segment 42, the energizing circuit of the slow releasing relay 39 is opened, and upon the engagement of the brush arm with the segment 44, release relay 37 is energized over a circuit from battery through the ring 40, brush arm and segment 44 of the distributor TD and the winding of re-

lease relay 37 to ground. The energization of release relay 37 opens the locking circuit of relay 35, which thereupon releases. Relay 39 is made slow in releasing so that its contact remains open until after the opening of the contact of the release relay 37. As the brush arm moves out of engagement with segment 44, release relay 37 is deenergized. When the brush arm engages segment 7, negative signaling current is connected with the common signaling path P. The automatic engagement selector switch H is now in condition to be seized by another trunk line, since trunk line L2 is disconnected therefrom, and the sending distributor TD is in normal condition.

Upon the operation of the differential polarized relay 50', due to the transmission of the first positive or starting impulse over the common signaling path P when the brush arm engages the starting segment 8, release magnet RDM' of the receiving distributor RD' is energized over a circuit from battery through the alternate contact of the differential polarized relay 50', segment 51', the brush arm, segment 53' and the winding of release magnet RDM' to ground. The attraction of the armature of the release magnet RDM' upon the energization thereof releases the brush arm of the receiving distributor RD' which is thereupon rotated through a complete cycle at the end of which the brush is stopped in its normal position. As the brush arm moves out of engagement with the segments 51' and 53' the release magnet RDM' is deenergized permitting the release of its armature preparatory to stopping the brush arm when it reaches its normal position. When the brush arm moves out of engagement with the segment 55', relay 58' is deenergized closing its contact which is common to the locking circuits of relays 61' to 66' inclusive. The armature of the differential polarized relay 50' remains in its normal position when negative signaling current is connected with the other end of the common signaling path P and moves to its alternate position whenever positive signaling current is connected with the other end of the common signaling path P. The brush arms of the sending and receiving distributors TD and RD' are being rotated at the same time and in synchronism. Therefore, when the brush arm of the sending distributor TD engages sending segments 2 and 5 to which negative signaling current is connected, the armature of the differential polarized relay 50' is in its normal position while the brush arm of the receiving distributor RD' engages the receiving segments 2' and 5'. Therefore, relays 62' and 65' are energized, the former over a circuit from battery through the normal contact of relay 50', common re-

ceiving ring 54', the brush arm, receiving segment 2' and the lower winding of relay 62' to ground, while relay 65' is energized over a similar circuit except that receiving segment 5' instead of 2' is included in its circuit. Relays 62' and 65' immediately lock up through their respective upper windings and alternate contacts and the contact of relay 58' to ground. Relay 62' in operating causes the energization of relays 70' to 73' inclusive, of the pyramid selecting relay 75 combination over a circuit from battery through the windings of these relays in series, upper normal contact of relay 89', and the lower contact of relay 62' to ground. When the brush arm of the receiving distributor RD' engages segments 56' and 57', signal receiving relay 85 operates over a circuit from negative signaling battery through the middle normal contact of relay 86', normal contact of relay 66', lower normal contact of relay 86', segment 56', the brush arm, segment 57', lower normal contact of relay 87', lower alternate contact of relay 65', the upper normal contact of relay 87', the lower normal contacts of relays 67' and 69', lower alternate contact of relay 73', upper normal contact of relay 81', a normal contact of switch K', signal receiving lead E'2 and the right-hand winding of signal receiving relay 85 to ground. Signal receiving relay 85 thereupon completes a locking circuit for itself from battery through its alternate contact and left-hand winding to ground, and causes the lighting of supervisory lamp 90 over a circuit from battery 100 through the alternate contact of signal receiving relay 85, lower normal contact of relay 91 and the lamp 90 to ground. The operation of signal receiving relay 85 also causes the energization of slow release relay 98 over a circuit from battery through the alternate contact of signal receiving relay 85, the normal contact of signal receiving relay 104 and the winding of relay 98 to ground. While signal receiving relay 104 110 is also energized in parallel with relay 85, it does not lock up for slow release relay 98 is not energized and relay 104 therefore performs no useful function at this time. The lighting of this lamp 90 is an indication 115 to the operator at the office Y that connection has been made with the proper trunk line L2 by the operator at the office X and is what is usually known as a "guard signal". When the brush arm moves out of engagement with the segments 56' and 57', the energizing circuits of relays 85 and 104 are opened causing the deenergization of relay 104 before slow release relay 98 closes its contact. When the brush arm engages the 125 segments 51' and 53', the armature of relay 50' is in its normal position since the brush arm of the sending distributor TD is in en-

gagement with segment r thereof and negative signaling current is connected with the common signaling path P , and the energizing circuit of the release magnet RDM' is 5 open. The engagement of the brush arm with the segment $55'$ causes the energization of the relay $58'$, which thereupon opens the locking circuits of relays $62'$ and $65'$. Relays $70'$ to $73'$, inclusive, are thereby deenergized 10 restoring the pyramid selecting relay combination to normal condition.

Connection of trunk line L2 with telephone line G.

- 15 Upon observing the lighted condition of the lamp 90 the operator at the office Y inserts plug 92 of the trunk line $L2$ into jack 93 of the telephone line G , causing the operation of relay 91 over a circuit from 20 battery through the winding of relay 91 , sleeve contacts of the plug 92 and jack 93 and the winding of cut-off relay 94 to ground. Relay 91 in operating opens the circuit of and extinguishes the lamp 90 .
- 25 This relay 91 , in closing its middle alternate contact, causes the operation of relay $24'$ over a circuit from battery through the normal contact or relay $25'$, winding of relay $24'$, contact of supervisory relay 95 and 30 the middle alternate contact of relay 91 to ground. Relay $24'$ in operating locks up over a circuit from battery through a middle alternate contact and its winding, the contact of supervisory relay 95 and the middle alternate contact of relay 91 to ground. 35 Relay $25'$ thereupon operates over a circuit from battery through a middle alternate contact of relay $24'$, resistance $26'$, and the winding of relay $25'$ to ground. This relay $25'$, upon being energized, locks up over a 40 circuit from battery through its left-hand alternate contact, resistance $26'$ and its own winding to ground. Relay $24'$ in operating connects positive battery with the signal control lead $C'2$, connects signal control lead $B'2$ with one terminal of the winding of relay $27'$, while relay $25'$ in operating grounds the signal control lead $A'2$ and the common start lead ST' . This start lead 45 and the signal control leads are associated with an automatic selector switch H' which controls the polarities connected with the sending segments of sending distributor TD' at the office Y . The automatic selector switch H' and the sending distributor TD' of the sending equipment SE' and the associated control apparatus thereof thereupon function in exactly the same manner as described in connection with selector switch H 55 and the sending distributor TD , to determine the code of and to transmit the coded signal over the common signaling path P . The code signal transmitted by the sending distributor TD' is the same as that trans-
- 65 mitted by the distributor TD upon the connection of the cord circuit F with the trunk line $L2$. After the transmission of this code signal, relays $24'$, $25'$ and $27'$ are energized and ground is disconnected from signal control lead $A'2$ and start lead ST' . The sending equipment SE' is now in normal condition, ready to be appropriated by any other trunk line which may initiate a signal at the office Y . 70
- This code signal transmitted over the common signaling path P from the office Y upon being received at the office X causes the differential polarized relay 50 to function in the same manner as previously described in connection with relay $50'$. The receiving distributor RD , local control apparatus thereof, locking relays 62 and 65 , and pyramid selecting relays 70 to 73 inclusive of the receiving equipment RE controlled by the relay 50 then function to select signal receiving lead $E2$ and to transmit thereover an impulse from negative signaling battery. This negative impulse traverses the left-hand or energizing winding of signal receiving relay 100 , which is thereby energized and locks up over a circuit from battery through the right-hand contact and winding thereof and the contact of relay 22 to ground. Upon the cessation of this negative impulse and the stopping of the brush arm of the receiving distributor RD , all apparatus of the receiving equipment RE is restored to normal condition ready to receive any other code signal and translate it into the appropriate signal of the proper 90 trunk line. Signal receiving relay 100 , upon being energized, closes its left-hand contact connecting resistance 99 in parallel with the winding of relay 22 , thereby reducing the 95 resistance in circuit with supervisory lamp 23 . This supervisory lamp is thereby lighted and now serves as a signal to the operator at the office X that connection has been established with the telephone line G and that the circuit is in condition for signaling the 100 station on the connected telephone line G .
- Operator at office X actuates ringing key.*
- The operator at office X upon observing the lighted condition of supervisory lamp 23 may actuate ringing key 101 , thereby causing the energization of ringing response relay 102 by means of ringing current from the source 103 . Relay 102 in operating 115 causes the energization of relay 30 which, at 120 its left-hand contact, opens the locking circuit of relay 27 which thereupon releases its armatures.
- Operator at office X restores ringing key.*
- Upon the restoration of the ringing key 101 to normal position, relay 102 releases its armature whereupon relay 30 is deener-

gized closing its contacts. The closure of the right-hand and middle contacts of the relay grounds the signal control lead A2 and the common start lead ST. The selector switch H and the sending distributor TD now function to transmit the same code signal transmitted when the cord circuit F was connected with trunk line L2, as previously described. During this operation, 5 relay 27 is energized over signal control lead B2 and locks up removing ground from signal control lead A2 and the start lead ST. At the conclusion of the transmission of the code signal, the control apparatus of the selector switch H, and the sending distributor TD are restored to normal condition ready 10 for use by any other trunk line initiating a signal at the office X. This transmitted code signal being received at the office Y causes the receiving distributor RD' locking relays and pyramid selecting relays to 15 function to select signal receiving lead E'2 and to transmit thereover a negative impulse, after which this receiving equipment is restored to normal condition. This negative 20 impulse over signal receiving lead E'2 traverses the energizing or right-hand winding of signal receiving relay 104, which energizes, and then holds up over a circuit 25 from battery through its left-hand winding and contact and the contact of slow release relay 98 to ground. The closure of the right-hand alternate contact of signal receiving relay 104 causes the energization of slow 30 release relay 105 over a circuit from battery through the alternate contact of signal receiving relay 85, right-hand alternate contact of signal receiving relay 104 and winding of relay 105 to ground. Relay 105 upon 35 being energized, causes the energization of ringing relay 106. Upon the opening of the normal contact of signal receiving relay 104, the energizing circuit of slow release relay 98 is opened so that this relay immediately 40 begins to release its armature. Upon the full release of the slow release relay 98 the holding circuit of signal receiving relay 104 is opened causing the release thereof. Signaling receiving relay 104 in 45 releasing its armatures opens the energizing circuit of slow release relay 105, which, when fully released, opens the energizing circuit of ringing relay 106. This combination 50 of slow release relays controlling and controlled by the signal receiving relay 104 determines the length of time that the ringing relay 106 is energized and therefore the length of time that ringing current is 55 connected with the telephone line G. During 60 the energization of ringing relay 106, a source of ringing current 107 is connected with the called telephone line G to cause the operation of the usual call bell at the station thereon (not shown).

Subscriber of telephone line G removes 65 receiver from switchhook.

The subscriber at the station on telephone line G in responding to the operation of the call bell thereat removes the receiver 70 from the switchhook, thereby causing the operation of supervisory relay 95 which opens the locking circuit of relay 24'. Relay 24' in releasing its armature connects negative signaling battery with signal control lead C'2 which is connected through a normal contact of the switch K' with the allotted contact on the sixth level of the selector H' of the sending equipment SE'. The opening of the middle alternate contacts 75 of relay 24' opens the locking circuit for relay 27' which thereupon releases its armatures, grounding the signal control lead A'2 and the common start lead ST'. The selector switch H' and the sending distributor 80 TD' of the sending equipment thereupon function to determine and transmit a coded signal over the common signaling path P to the office X. During this operation the signal control lead B'2 is temporarily 85 grounded, short-circuiting the winding of relay 25'. Relay 25' is thereby deenergized, releasing its armatures removing ground from the signal control lead A'2 and the common start lead ST'. Relays 24', 25' 90 and 26' are now deenergized, and upon the conclusion of the transmission of the coded signal, the control apparatus of the selector switch H', and the sending distributor TD' of the sending equipment SE' are in normal 95 position ready for use by any other trunk line initiating a signal at the office Y. The transmitted code signal comprises six impulses, the first, third and fourth of which are positive and the second, fifth and sixth 100 are negative.

This code signal being received at the office X, the receiving distributor RD in coöperation with relay 50 causes the energization and locking up of locking relays 62, 65 and 110 66, the first two of which cause the pyramid selecting relays of the receiving equipment RE to select the signal receiving lead E2, and the third of which, relay 66, in coöperation with the receiving distributor RD, 115 connects with and transmits over this selected signal receiving lead E2 an impulse of positive signaling current. This positive impulse traverses the left-hand winding of signal receiving relay 100. The signal receiving relay 100 is locked up at this time. The windings of this relay are so related 120 that with the relay locked up when a positive impulse is transmitted through its left-hand winding the relay is rendered differential and releases its armatures. The release of the signal receiving relay 100 disconnects the resistance 99 from parallel 125

relation with the winding of relay 22 thereby increasing the resistance in circuit with the supervisory lamp 23. The lamp is thereby extinguished. The extinguishment 5 of the supervisory lamp 23 serves as a signal to the operator at the office X that the called subscriber has responded.

Subscriber restores receiver to switchhook.

- 10 At the conclusion of the conversation, the subscriber at the station on telephone line G restores the receiver to the switchhook thereby opening the circuit of and deenergizing supervisory relay 95. Upon 15 the closure of the contact of this supervisory relay, relay 24' operates over the circuit previously traced in connection with the establishing of a connection between trunk line L2 and the telephone line G. 20 Relay 24', upon being energized locks up causing the energization and locking up of relay 25'. Positive signaling current is now connected with signal control lead C'2, and the start lead ST' and the signal control lead A'2 are grounded. The automatic selector switch H' and the sending distributor TD' of the sending equipment SE' now function to determine and transmit a code signal over the common signaling path P to the office X. This code signal comprises six impulses, the first, third, 25 fourth and sixth of which are positive and the second and fifth negative. During the operation of determining the code signal, signal control lead B'2 is grounded, causing the energization and locking up of relay 27' which removes ground from the start lead ST' and the signal control lead A'2. 30 The transmitted code signal being received at the office X, the differential polarized relay 50 co-operates with the receiving distributor RD, the locking relays and the pyramid selecting relays of the receiving 35 equipment RE to select receiving lead E2 and to transmit thereover a negative impulse, which causes the energization and locking up of the signal receiving relay 100. After the transmission of this negative 40 impulse over the signal receiving lead E2, all apparatus of the receiving equipment RE is restored to normal condition ready to receive another code signal. The energization of the signal control relay 100 45 connects resistance 99 in parallel with the winding of relay 22, thereby causing the supervisory lamp 23 to be lighted to furnish a disconnect signal to the operator at the office X. 50 Operator at office X disconnects cord circuit F from trunk line L2.

Upon observing the lighted condition of the supervisory lamp 23, the operator at 55 the office X may withdraw the plug 20 of

the cord circuit F from the jack 21 of the trunk line L2, whereby relay 22 is deenergized and the supervisory lamp 23 extinguished. The deenergization of relay 22 opens the circuit of and causes the deenergization of relay 24. Relay 24, in releasing its middle armature, opens the locking circuit of and deenergizes relay 27. Negative signaling current is now connected with signal control lead C2, and the start lead 70 ST and the signal control lead A2 are grounded.

The automatic selector switch H and the sending distributor TD, together with the control apparatus thereof, now function to 80 determine and transmit a coded signal over the common signaling path P to the office X. During the operation of determining the code of this coded signal, signal control lead B2 is grounded through brush b of the 85 selector switch H, middle alternate contact of relay 85 and the contacts of slow release relay 86 and release relay 87. The grounding of this signal control lead B2 short-circuits the winding of relay 25, which is 90 thereby deenergized and releases its armatures, removing ground from the start lead ST and the signal control lead A2. The code signal transmitted by the sending distributor TD comprises 6 impulses, the first, 95 third and fourth of which are positive and the second, fifth and sixth negative. After the transmission of this code signal, the control apparatus of the selector switch H and the sending distributor TD and its associated control apparatus are restored to normal condition ready to be associated with any other trunk line initiating a signal at the office X.

The transmitted code signal causes differential polarized relay 50' and receiving distributor RD' and its associated control apparatus to co-operate to cause the energization and locking up of locking relays 62', 63' and 63', these locking relays being controlled from the respective individual receiving segments 2', 5' and 6' of the receiving distributor RD'. Pyramid selecting relays 70' to 73' inclusive are energized upon the energization of locking relay 62' and co-operate with the energized locking relay 65' to select the signal receiving lead E'2, over which, upon the engagement of the brush arm of the receiving distributor RD' with the segments 56' and 57', an impulse of 110 positive signaling current is transmitted. This positive impulse traverses right-hand windings of signal receiving relays 85 and 104. Signal receiving relay 85 is, at this time, locked up. The relation of the windings of this relay is such that when positive signaling current traverses its right-hand winding when locked up, the relay is rendered differential and releases its armatures. The release of the armature of this relay 115 120 125 130 135

- 85, due to a positive impulse traversing its right-hand winding, causes supervisory lamp 90 to be lighted over a circuit from battery through the normal contact of signal receiving relay 85, the lower alternate contact of relay 91 and the lamp 90 to ground. The lighting of this lamp 90 serves as a disconnect signal to the operator at the office Y. The opening of the alternate contact of signal receiving relay 85 causes the de-energization of slow release relay 98. While signal receiving relay 104 is energized, due to the positive impulse traversing its right-hand winding, this relay is rendered differential immediately upon the closure of its left-hand contact and is thereupon de-energized. Consequently, the energization of a signal receiving relay 104 at this time performs no useful function. Upon the return of the brush arm of distributor RD' to normal position, relay 58' is energized opening the locking circuits of and de-energizing the locking relay 62', 65' and 66'. The de-energization of locking relay 62' causes the de-energization of pyramid selecting relays 70' to 73' inclusive. All apparatus for the receiving equipment is therefore now in normal condition ready for receiving any further code signals transmitted over the common signaling path P.

Operator at office Y disconnects trunk line L2 from telephone line G.

- The operator at the office Y upon observing the lighted condition of the supervisory lamp 90 may withdraw the plug 92 of trunk line L2 from the jack 93 of the telephone line G, whereupon relay 91 and cut-off relay 94 release their armatures. The release of relay 91 opens the circuit of and extinguishes supervisory lamp 90. The opening of the middle alternate contact of relay 91 causes the de-energization of relays 24' and 27'. Negative signaling current is therefore connected with signal control leads C'2, and start lead ST' and signal control lead A'2 are grounded.

- The automatic selector switch H' and the sending distributor TD' of the sending equipment SE' thereupon function to determine and transmit over the common signaling path P, a code signal of six impulses, the first, third and fourth of which are positive, and the second, fifth and sixth of which are negative. Upon the termination of this code signal, signal control lead B'2 is grounded in the manner hereinbefore described and short-circuits the winding of relay 25'. Relay 25' is thereby de-energized and releases its armatures, removing ground from the start lead ST' and the signal control lead A'2. At the conclusion of the transmission of the coded signal all apparatus of the sending equipment SE' is restored to normal condition.

Upon the reception of the transmitted code signal at the office X differentially polarized relay 50 co-operates with the receiving equipment RE to select the signal receiving lead E2 and to transmit thereover a positive impulse which traverses the left-hand winding of the signal receiving relay 100. Since the locking circuit of this signal receiving relay 100 is open at the contact of relay 22, the energization thereof at this time performs no useful purpose.

The operations described above with reference to building up a connection over the trunk line L2 with the telephone line G and the breaking down of such a connection are characteristic of those taking place in building up and breaking down a connection over any one of the trunk lines to which the signaling path P is common. The only essential difference in operation, so far as the establishment of connections over the different trunk lines is concerned, is that different code signals are employed for the different trunk lines, and while this invention is not limited to any particular arrangement of code signals, the codes shown in the following table have been found to be very satisfactory for a total of thirty-two trunk lines served by the same common signaling path.

95

130

In this table, the numbers in the first column indicate the numbers assigned to the trunk lines, while the numbers in the remaining columns indicate the order of the negative impulses in each group of six. The number "0" appearing in the last line in the second, third and fifth columns of the table means that no negative impulses are trans-

125

mitted. The various code signals represented in the table are determined by the polarities connected with the contacts of the first to sixth levels of the automatic selector switches H and H', the polarity connected with the contacts of the sixth levels being further determined by the position of the pole changing relays 24 and 24' of the various trunk lines.

10 *Testing equipment and operation.*

Referring now to the testing equipment and to the operation thereof it will be recalled that there is provided for each trunk line a switching device K located at the office X and a similar switching device K' located at the office Y. Each of these switching devices comprises an upper and lower row of individual switches. The normal contacts of the upper individual switches of the switching device K₂ associated with trunk line L₂, connect the signal control leads A₂, B₂ and C₂, with the allotted contacts on the a, b and first to sixth levels of the automatic selector switch H; the signal receiving lead E₂ with the upper normal contact of the pyramid selecting relay 81; and the starting lead ST with the start magnet 28 of the selector switch. The normal contacts of the lower individual switches of the switching device K connect the individual signal receiving relay and normally open signal initiating keys M₂ and N₂ of the testing equipment TE with the duplicate receiving and sending equipment DRE and DSE respectively.

In a similar manner, the individual switches of the switching device K'2 associates the signal control, receiving and start leads of trunk line L₂ at the office Y with the sending equipment SE' and the upper normal contact of pyramid selecting relay 81', and also associates the signal receiving relay D'2 and the signal initiating keys M'2 and N'2 with the duplicate receiving and sending equipment DRE' and DSE'. In like manner, other switching devices K and K' associate the signal control, signal receiving and start leads with the regular sending and receiving equipment, and the testing equipment thereof with the duplicate sending and receiving equipment.

Assuming that it is desired to test the selector switch H, the sending distributor TD and the receiving distributor RD' to determine whether this apparatus functions properly when sending code signals corresponding to all trunk lines to which this apparatus is common, all switching devices K and K' are actuated to open normal and close alternate contacts of their individual switches. The opening of the normal contacts of the upper individual switches disconnects the signal control, signal receiving and start leads associated with the individual

trunk lines from the selector switches and receiving distributors associated with the common signaling path P, while the closure of the alternate contacts of these particular individual switches connects these leads with similar duplicate sending and receiving equipment associated with the duplicate common signaling path DP. The opening of the normal contacts of the lower individual switches disconnects the signal initiating keys and signal receiving relays of the testing equipment for the individual trunk lines from the duplicate sending and receiving equipment associated with the duplicate common signaling path DP, while the closure of the alternate contacts of the lower individual switches connects the testing equipment with the sending and receiving equipment associated with the common signaling path P.

The signal initiating keys M at the office X individual to the trunk lines are then actuated one after the other in a definite predetermined order and if the signal lamps O' at the office Y light in the same predetermined order it is known that the code signals were correctly set up at the office X, transmitted over the signaling path P and received and translated at the office Y. Upon actuation each signaling initiating key M is held actuated until the signal lamp 120 common to these keys is lighted by the energization of its controlling relay 119. The lighting of this common lamp indicates to the testing operator that the correct code combination determined by the actuated signal initiating key has been set up and that this code combination is being transmitted by the sending distributor. Upon the restoration of an actuated signal initiating key M to normal position after the lighting of the lamp 120, relay 119 releases extinguishing the lamp 120. For further determining the correctness with which the equipment functions the two signal initiating keys for the various trunk lines at the office X are actuated simultaneously and in a definite predetermined order. If the equipment is functioning properly the lamps O' at the office Y will be extinguished in the order in which the pairs of signal initiating keys are actuated. Each pair of keys is held actuated until the associated common lamp 120 lights, when the keys are restored to normal position extinguishing the lamp.

What actually takes place when one of the signal initiating keys is actuated will now be described. In this description, the results of the actuation of signal initiating key M₂ for trunk line L₂ will be considered. The actuation of this key M₂ causes the energization of start magnet 28 over circuit from battery through the winding of start magnet 28, common start lead ST, alternate contact of the lower individual switch 110, 130

left-hand normal contact of signal receiving relay 119 and the lower contact of signal initiating key M2 to ground. Start magnet 28 in operating closes the operating circuit of the motor magnet MM, which thereupon advances the brushes of the selector switch H until brush *a* engages one of its associated contacts which is grounded by the actuation of the signal initiating key M2. Relay 35 thereupon operates over a circuit from battery over the left-hand winding of relay 35, brush *a*, alternate contact of the lower individual switch 111, upper contact of signal initiating key M2 and the right-hand normal contact of signal receiving relay 119. Relay 35 immediately opens the operating circuit of the motor magnet MM which prevents the further advance of the brushes of the selector switch H. The closure of the middle alternate contact of relay 35 causes the operation of signal receiving relay 119 over a circuit from battery through the right-hand winding of relay 119, middle contact of the signal initiating key M2, alternate contact of the individual switch 112, contact engaged by brush *b*, middle alternate contact of relay 35 and the contacts of slow release relay 39 and release relay 37 to ground. Signal receiving relay 119 upon being energized instantly completes a locking circuit from battery through its left-hand winding and left-hand alternate contact and the lower contact of signal initiating key M2 to ground. The lamp 120 is lighted in parallel with the locking winding of this relay 119. The lighting of this lamp indicates to the testing operator at the office X that the start relay 35 which controls the energization of the release magnet TDM of the sending distributor TD has been energized so that the operator may thereupon restore the signal initiating key M2 to its normal position, whereupon signal receiving relay 119 is deenergized and releases its armature extinguishing the lamp 120. At the time relay 119 operated the opening of the normal contacts thereof opened the energizing circuits of the start magnet 28 and the start relay 35. Upon the opening of these energizing circuits, start magnet 28 releases its armature but start relay 35 remains energized due to the locking circuit established through its right-hand winding upon its energization. After the lighting of the lamp 120, the signal initiating key may be restored to normal position releasing relay 119, extinguishing the lamp 120 and disconnecting relay 119 from the contacts of the selector switch H.

The brushes 1, 3, 4 and 6 of the switch H now connect positive battery with the respective individual sending segments 1, 3, 4 and 6 of the sending distributor TD.

65 Positive battery is connected with the sixth

segment through the normal contact of signal initiating key N2 of the testing equipment, signal control lead C2, allotted contact of the sixth level engaged by the brush 6. The closure of the right-hand alternate contact of the start relay 35 causes the energization of the release magnet TDM of the sending distributor TD. The sending distributor TD thereupon functions in the manner hereinbefore described to transmit 70 over the common signaling path P, a code signal comprising six impulses, the first, third, fourth and sixth of which are positive and the second and fifth negative. After the transmission of this code signal 80 the sending distributor TD is restored to normal condition together with the control apparatus thereof, start relay 35, slow release relay 39 and release relay 37.

If the receiving equipment is in proper 85 working order, the reception of this transmitted coded signal at the office Y, by means of the differential polarized relay 50', causes this relay to coöperate with the receiving distributor RD', whereupon, during the rotation of the brush arm of this receiving distributor, relay 58' is released, locking relays 62' and 65' are energized and locked up. The energization of locking relay 62' causes the energization of pyramid selecting 95 relays 70' to 73' inclusive. The pyramid selecting relays thereupon coöperate with the energized locking relay 65' to select the signal receiving lead E'2. As the brush arm of the receiving distributor RD' engages the 100 segments 56' and 57' thereof a negative impulse of signalling current is transmitted over the selected signal receiving lead E'2, through the alternate contact of the lower individual switch 114' and the right-hand 105 winding of signal receiving relay D'2 to ground. Signal receiving relay D'2 upon being energized, completes a locking circuit from battery through its left-hand winding and left-hand contact to ground. This relay in closing its right-hand contact causes lamp O'2 to light, indicating to the testing operator at the office Y that the transmitted code signal has been properly received. With the brush arm of the receiving distributor RD' returned to normal position, 115 relay 58' is energized, causing the deenergization of locking relays 62' and 65' whereupon pyramid selecting relays 70' to 73' are deenergized. The receiving equipment 120 is then in normal condition.

What actually takes place in the system when an associated pair of signal initiating keys are actuated, for example keys M2 and N2 individual to trunk line L2, will now be 125 considered. The actuation of the signal initiating key M2 causes the control apparatus of the selector switch H to function in the manner hereinbefore described, while the actuation of the signal initiating key 130

N2 serves merely to connect negative instead of positive signaling current through the alternate contact of the individual switch 113 with the allotted contact of the sixth 5 level of the selected switch. Start relay 35 is energized as before described when brush *a* engages the contact grounded by the actuation of key M2, stops the motor magnet MM and causes the operation of the signal receiving relay 119, which serves the same purpose as when signal initiating key M2 alone is actuated. The operation of the start relay 35 causes the sending distributor TD to function as before to transmit over 10 the common signaling path P a code signal of six impulses, the first, third and fourth of which are positive and the second, fifth and sixth negative.

This code signal being received by the 20 office Y, the receiving distributor RD' and the differential polarized relay 50' coöperate to select the receiving lead E'2, and to cause the energization and locking up of locking pole changing relay 66' which determines 25 the polarity of signaling impulse to be transmitted over the selected signal receiving lead E'2. Upon the engagement of the brush arm with segments 56' and 57' of the receiving distributor RD' positive signaling current is connected with the right-hand winding of the signal receiving relay D'2 over a circuit from positive battery through the upper normal contact of relay 86', lower alternate contact of pole changing relay 66', 30 lower normal contact of relay 86', segment 56', the brush arm, segment 57, lower normal contact of relay 87', lower alternate contact of locking relay 65', upper normal contact of relay 87', lower normal contacts 35 of relays 67' and 69', lower alternate contact of relay 73', upper normal contact of relay 81', signal receiving lead E'2, alternate contact of individual switch 114' and the right-hand winding of signal receiving 40 relay D'2 to ground. This signal receiving relay D'2 is similar to signal receiving relays 85, 100 and 104 and when locked up is rendered differential by the transmission of a positive impulse through its right-hand winding. The signal receiving relay D'2 therefore releases its armatures opening the circuit of and extinguishing the lamp O'2. 50

If the improper code signal is set up by the actuation of any signal initiating key 55 M at the office X, the lamp of the testing equipment at the office Y will not be lighted. The testing operator at the office X will be so advised, and steps will be taken to locate and clear the trouble. It will be apparent, 60 of course, that the sending and receiving equipment SE' and RE may be similarly tested by first actuating the signal initiating keys M' of the testing equipment TE' at the office Y in a predetermined order to light the 65 lamps O in the testing equipment TE at the

office X, and then simultaneously actuate the associated pair of signal initiating keys M' and N' in a predetermined order to extinguish the lamps O.

70

Speed checking.

For the purpose of determining whether the sending and receiving distributors TD and RD' at the opposite ends of the common signaling path P operate in synchronism, there is provided at the office X a key 122 which coöperates with the sending distributor TD, a key 121 at the office Y which coöperates with the receiving distributor RD' and a plurality of signaling 75 lamps 131' to 136', inclusive, as will more fully hereinafter appear. These keys, the signal lamps and the distributors coöperate with the testing equipment TE, the automatic selector switch H and the locking relays 61' to 66' in checking the speed of the distributors.

When it is desired to check the speed of the sending and receiving distributors TD and RD', the testing operators at the two 90 offices actuate the switching devices K and K' to associate the trunk lines with the duplicate sending and receiving equipments and the duplicate common signaling path DP and to associate the sending and receiving equipment of the common signaling path P with the testing equipments TE and TE'. The testing operator at the office X then actuates key 122 which is preferably of the locking type. The actuation of this key 95 energizes the release magnet TDM which permits the free rotation of the brush arm of the sending distributor TD. The testing operator at the office Y actuates key 121 which is also preferably of the locking type. 100 The actuation of this key energizes the release magnet RDM' which permits the free rotation of the brush arm of the receiving distributor RD'. The actuation of the key 121 also energizes relays 86' to 89', inclusive, 110 disconnecting the pyramid selecting relays 67' to 81' and their associated circuits from the contacts of the locking relays 61' to 66' and connects therewith the signaling lamps 115 131' to 136', inclusive. The sending and receiving equipments associated with the common signaling path P are now in condition for checking the speed of the sending and receiving distributors TD and RD'.

The operator at the office X now actuates 120 one of the individual signal initiating keys M, for example, key M1 (not shown), which causes the control apparatus of the automatic selector switch H to function to advance the brushes of this switch until brush *a* thereof engages the contact grounded by the actuation of the signaling initiating key M1, whereupon the brushes are stopped in this position. By reference to the table of signals, it will be observed that for trunk 130

line L1, negative signaling current is connected with the third individual sending segment of the sending distributor TD, while positive signaling current is connected with the first, second, fourth, fifth and sixth individual sending segments. Therefore, during each revolution of the brush arm of the sending distributor TD, a negative impulse will be transmitted over the common 5 signaling path P when the brush arm engages the individual sending segment 3. Since the brush arms of the sending and receiving distributors TD and RD' may not be released at the same time, these brush 10 arms may not, of course, be rotating in phase although they may be in synchronism. So that at the time the negative impulse is sent over the common signaling path P from the individual sending segment 3 of the 15 sending distributor TD, the brush arm of the receiving distributor RD' may be engaging any one of its six individual receiving segments 1' to 6', inclusive. If the brush arm of the receiving distributor RD' 20 engages individual receiving segment 5' when the negative impulse is transmitted over the common signaling path P from the individual sending segment 3 of the sending distributor TD, then locking relay 65' 25 is energized and locks up through its upper alternate contact and the contact of relay 58' to ground. The signal lamp 135' controlled by this locking relay is therefore lighted. The relay 65' will remain locked 30 up and the lamp 135' controlled thereby will be lighted until the brush arm engages ring 52', and segment 55' of the receiving distributor RD', whereupon relay 58' energizes, releasing the relay 65' and extinguishing 35 the lamp 135'. If this signal lamp 135' is lighted during each revolution of the distributors, then the distributors are in synchronism.

However, should first one and then another of the group of signal lamps 131' to 136' inclusive, be lighted during the continued rotation of the brush arms, the testing operator knows that the distributors are not in synchronism. When not in synchronism, the order in which these lamps light 40 indicates to the testing operator which of the two brush arms is being rotated more rapidly than the other. For example, should the lamps be lighted in the order of their numbers then the brush arm of the receiving distributor RD' is moving faster than that of the sending distributor TD, while if in the reverse order, then the brush arm of the receiving distributor is moving slower 45 than that of the sending distributor. The testing operator then proceeds to make the necessary adjustments to bring them in synchronism, which is indicated by the continued lighting and extinguishing of the same lamp. After the operation of check- 50

ing speeds of the distributors is concluded, the system may be restored to its normal position by the restoration of keys 121 and 122, signal initiating key M1 and switching devices K and K' to their normal positions. 70

What is claimed is:

1. In a telephone system, in combination, a plurality of trunk lines and a signaling path common thereto extending between two stations, means at one station for transmitting over the signaling path code signals, individual to the different trunk lines, each code signal comprising a plurality of current impulses, means common to the trunk lines for determining the character of some of the impulses of each code signal, and means individual to each trunk line and controlled thereby for determining the character of another of the impulses of each code signal. 75
2. In a telephone system, in combination, a plurality of trunk lines and a signaling path common thereto extending between two stations, means at one station for transmitting over the signaling path code signals, individual to the different trunk lines, each code signal comprising a plurality of current impulses, a code-determining switching device common to the trunk lines for determining the polarity of some of the impulses of each code signal, and a pole-changing relay individual to each trunk line and controlled thereby for determining the polarity of another of the impulses of each code signal. 80
3. In a telephone system, in combination, a plurality of trunk lines and a signaling path common thereto extending between two stations, means at one station for transmitting over the signaling path code signals individual to the different trunk lines, each code signal comprising a plurality of current impulses, means individual to each trunk line and controlled thereby for determining the character of one impulse of each code signal, and a switching device common to all and controlled by each of the trunk lines for determining the character of the remaining impulses of each code signal. 85
4. In a telephone system, in combination, a plurality of trunk lines and a signaling path common thereto extending between two stations, means at one station for transmitting over the signaling path code signals individual to the different trunk lines, each code signal comprising a plurality of current impulses, a pole-changing relay individual to each trunk line and controlled thereby for determining the polarity of one impulse of each code signal, and a switching device common to all and controlled by each of the trunk lines for determining the polarities of the remaining impulses of each code signal. 90

5. In a telephone system, in combination, a plurality of trunk lines and a signaling path common thereto extending between two stations, a sending distributor having individual sending contacts for transmitting over the signaling path code signals individual to the different trunk lines and comprising current impulses equal in number to the number of individual sending contacts, a switching device having sets of stationary contacts and a coöperating movable contact for each set connected with the individual contacts of the sending distributor for determining the character of the impulses of each code signal, and means individual to each trunk line and controlled thereby for determining the character of current connected with the stationary contacts associated with one of the movable contacts.
- 10 6. In a telephone system, in combination, a plurality of trunk lines and a signaling path common thereto extending between two stations, a sending distributor having individual sending contacts for transmitting over the signaling path code signals individual to the different trunk lines and comprising a plurality of current impulses equal in number to the number of individual sending contacts, a selecting switch common to all and controlled by each of the trunk lines and comprising a set of movable contacts connected with the individual contacts of the sending distributor and a plurality of stationary contacts coöperating with each movable contact for determining the polarities of the impulses of each code signal, and a pole-changing switch individual to each trunk line and controlled thereby for determining the polarity of current connected with the stationary contacts coöperating with one of the movable contacts.
- 15 7. In a telephone system, in combination, a plurality of trunk lines and a signaling path common thereto extending between two stations, means at one station for transmitting over the signaling path code signals individual to the different trunk lines, each code signal comprising a plurality of current impulses, a switching device having movable contacts and a plurality of coöperating stationary contacts for each movable contact for controlling the code of the signals transmitted by the sending means, means responsive to each change in condition of one of the trunk lines for causing the movable contacts to engage the same stationary contacts, and means external to the switching device and responsive to changes in the trunk lines for varying the code of the signal to be transmitted.
- 20 8. In a telephone system, in combination, a plurality of trunk lines and a signaling path common thereto extending between two stations, means at one station for transmitting over the signaling path code signals individual to the different trunk lines, each code signal comprising a plurality of current impulses equal in number to the number of individual sending contacts, a switching device common to the trunk lines comprising sets of stationary contacts and a coöperating movable contact for each set of stationary contacts, sources of positive and negative signaling current connected with the various stationary contacts in predetermined order for determining the polarities of current connected with all but one of the individual sending contacts of the sending distributor, and pole-changing switches individual to the trunk lines for determining the polarity of current connected with the remaining individual sending contact of the sending distributor.
- 25 9. In a telephone system, in combination, a plurality of trunk lines and a signaling path common thereto extending between two stations, a signal sending device at one station having individual contacts for transmitting over the signaling path code signals individual to the different trunk lines, each code signal comprising a plurality of current impulses equal in number to the number of individual sending contacts, a switching device common to the trunk lines comprising sets of stationary contacts and a coöperating movable contact for each set of stationary contacts, sources of positive and negative signaling current connected with the various stationary contacts in predetermined order for determining the polarities of current connected with all but one of the individual sending contacts of the sending distributor, and pole-changing switches individual to the trunk lines for determining the polarity of current connected with the remaining individual sending contact of the sending distributor.
- 30 10. In a telephone system, in combination, a plurality of trunk lines and a signaling path common thereto extending between two stations, a sending device at one station for transmitting over the signaling path code signals individual to the different trunk lines, a switching device common to the trunk lines and comprising stationary contacts divided into groups each containing one contact for each trunk line and a coöperating movable contact for each group, means controlled by each change in condition of any one of the trunk lines for causing each movable contact to come to rest in engagement with its coöperating stationary contact individual to the controlling trunk line, and means individual to and responsive to changes in condition of the controlling trunk line and coöperating with the individual contact of one group for determining the code of the signal to be transmitted.
- 35 11. In a telephone system, in combination, a plurality of trunk lines extending between two stations, a common signaling system for the trunk lines comprising a signaling path

- extending between the stations and means at each end of the signaling path for transmitting and receiving thereover code signals individual to the different trunk lines, 5 a duplicate common signaling system, means for testing each common signaling system, switching devices normally maintaining the first-mentioned common signaling system in operative relation to the trunk lines and the testing means in operative relation to the duplicate signaling system, and means for actuating the switching devices for disconnecting the first-mentioned signaling system, from and connecting the other 10 signaling system with the trunk lines and for simultaneously disconnecting the testing means from the second and connecting it with the first signaling system.
12. In a telephone system, in combination, 20 a plurality of trunk lines extending between two stations, signal-initiating means for the trunk lines at one station; signaling means common to the trunk lines comprising a signaling path extending between the two 25 stations, means for transmitting the signals initiated by the trunk lines into code signals individual to the initiating trunk lines and for transmitting the code signals over the common signaling path, means at the other 30 station for receiving and translating the transmitted code signals into signals individual to the initiating trunk lines; testing means comprising signal-initiating means at the one station, and signal-receiving and 35 signaling devices therefor at the other station; and switching apparatus for disassociating the signaling means from the trunk lines and associating the signaling means with the testing means.
- 40 13. In a telephone system, in combination, a plurality of trunk lines extending between two stations, signal-initiating means for the trunk lines at one station; signaling means common to the trunk lines comprising a signaling path extending between the two stations, means for translating the signals initiated by the trunk lines into code signals individual to the initiating trunk lines and for transmitting the code signal over the common 45 signaling path, means at the other station for receiving and translating the transmitted code signals into signals individual to the initiating trunk line; and testing means for the signaling means comprising 50 keys at one station for initiating the same signals initiated by the signal-initiating means of the trunk lines for controlling the code signal translating and transmitting means, a signaling device at the one station 55 responsive to the operation of the translating and transmitting means, and a signal control relay at the other station responsive to the transmitted code signal.
14. In a telephone system, in combination, 60 a plurality of trunk lines extending between two stations, signal-initiating means for the trunk lines at one station; signaling means common to the trunk lines comprising a signaling path extending between the two stations, means for translating the signals initiated by the trunk lines into code signals individual to the initiating trunk lines and for transmitting the code signals over the common signaling path, means at the other station for receiving and translating the transmitted code signals into signals individual to the initiating trunk lines; and testing means for the signaling means comprising pairs of keys equal in number to the number of trunk lines for initiating the same signals initiated by the signal-initiating means of the trunk lines whereby the code signal translating and transmitting means are controlled by each pair of keys, and a signal control relay at the other station energized in response to a transmitted code signal upon the actuation of one key of a predetermined pair and deenergized in response to another transmitted code signal when both keys of the same pair are actuated.
15. In a signaling system, in combination, a plurality of trunks extending between two stations, a signaling path common to said trunks, distributing means at each of the stations, signaling means at one station associated with the distributing means thereat and responsive to a predetermined permutation of impulses transmitted by the other distributing means when said distributing means are in unison, other signaling means at the one station common to said trunks and associated with the distributing means thereat and responsive to a like permutation of impulses transmitted by said other distributing means when the associated distributing means is leading the other and still other signaling means at the one station common to said trunks and associated with the distributing means thereat and responsive to a like permutation of impulses transmitted by the other distributing means when the associated distributing means is lagging behind the other.
16. In a signaling system, in combination, a plurality of trunks extending between two stations, a signaling path common to said trunks, a rotatable sending distributor at one station, a rotatable receiving distributor at the other station, and signaling devices common to said trunks and associated with the receiving distributor and selectively responsive to like predetermined permutations of impulses transmitted by the sending distributor depending on whether the distributors are rotating in unison or whether the receiving distributor is leading or lagging behind the sending distributor.
17. In a signaling system, in combination, a plurality of trunks extending between two stations, signal-initiating means for the trunk lines at one station; signaling means common to the trunk lines comprising a signaling path extending between the two stations, means for translating the signals initiated by the trunk lines into code signals individual to the initiating trunk lines and for transmitting the code signals over the common signaling path, means at the other station for receiving and translating the transmitted code signals into signals individual to the initiating trunk lines; and testing means for the signaling means comprising pairs of keys equal in number to the number of trunk lines for initiating the same signals initiated by the signal-initiating means of the trunk lines whereby the code signal translating and transmitting means are controlled by each pair of keys, and a signal control relay at the other station energized in response to a transmitted code signal upon the actuation of one key of a predetermined pair and deenergized in response to another transmitted code signal when both keys of the same pair are actuated.

stations, a signaling path common to said trunks, a rotatable sending distributor at one station, a rotatable receiving distributor at the other station, a signaling device associated with the receiving distributor and responsive to a predetermined permutation of impulses transmitted by the sending distributor when the two distributors are rotating in unison, a second signaling device common to said trunks and associated with the receiving distributor and responsive to a like permutation of impulses when the receiving is lagging behind the sending distributor. 15

10

like permutation of impulses when the receiving is leading the sending distributor, and a third signaling device common to said trunks and associated with the receiving distributor and responsive to a like permutation of impulses when the receiving is lagging behind the sending distributor. 15

In witness whereof I hereunto subscribe my name this 17th day of September A. D., 20 1919.

WILLIAM L. DODGE.
